UNITED STATES PATENT OFFICE.

JOHN L. TUFTS, OF WESTBORO, MASSACHUSETTS.

PROCESS FOR THE TREATMENT OF FIBERS.

Application filed November 15, 1922. Serial No. 601,040.

My invention relates to processes for the treatment of fibers and devices suitable therefor and refers particularly to processes for the washing and scouring of wool and apparatus applicable for the proper carrying out of my processes.

One object of my invention is a process for the wet treatment of wool whereby it may be washed and scoured by a new and novel method, resulting in economy of treatment and efficiency of results.

These and other objects of my invention and its adaptability for the treatment of various fibers will be evident upon a consideration of my specification and its accompanying drawings.

Without limiting my process to the scouring of wool, I will describe its application for that purpose as a means for properly presenting my invention.

Wool is usually scoured by passing it through a series, or plurality, of bowls each containing a solution of the desired scouring materials such as soaps and alkaline solutions, the wool being subjected to a squeeze-roller pressure in passing from one bowl to the next bowl, in order to partially free it from adhering and absorbed liquid and impurities.

During this process, the liquid contents of each bowl becomes constantly more concentrated with the added chemicals and salts in conjunction with the salts, greases, waxes, &c., freed from the wool, while the removed dirt and other insoluble and objectionable matter collect within the bowl.

It is evident that this process results in the rapid production of a liquor that is totally unfit for the cleansing or scouring of the wool, and that, therefore, it is necessary to remove the liquor from the bowl and recharge it with a new scouring liquid.

This process, therefore, among many other objectionable features, possesses the disadvantage of loss of efficiency of the scouring products and loss of time incident to bowl solution removal.

My process overcomes the above-mentioned and many other defective features of the generally employed processes and presents a means whereby the wool can be improved in quality of cleanliness with economy of chemicals, time, labor and operative

expenses and with a greater and more simple recovery of the valuable by-products of the scouring process.

My process may be followed either intermittently or continuously, and is particularly well adapted for the more economical and rapid continuous process of treatment.

In a general way, my process is practical in a series, or plurality, of ordinary scouring bowls, each having a foraminous false bottom and an outlet pipe, or outlet pipes, therefrom, squeeze rollers being positioned between each pair of adjacent bowls, so that the greater portion of the liquid carried by the wool in its passage from one bowl to another bowl will be pressed out, thus removing a large quantity of mixed fats, chemicals, solid and liquid impurities prior to the wool entry into the next bowl. Any suitable wool moving device, such as rakes or otherwise, may be employed and the bowls have liquid-carrying means between adjacent bowls.

I collect the liquors from the squeeze-roller between the first two bowls and pass them through a centrifugal which will divide them into three portions, viz: mud which may be discarded, or worked, for secondary products if desired; a grease mixture which contains grease and the "cleaned liquor" carried thereby which latter contains the soluble salts and soaps; and the "cleaned" liquor. The "cleaned" liquors containing the washing and scouring ingredients and practically freed from deleterious materials obtained from the centrifugal separation are returned to the forward portion of the first bowl, in order that their full efficiency may be exercised upon the uncleansed wool. This operation may be continuous and work automatically upon the liquid directly as obtained from the first squeeze rollers, or it may be allowed to collect in tanks and worked therefrom as desired.

I collect the liquor from each other pair of squeeze rollers and conduct it into the forward part of the bowl from which it was removed by the wool.

The mud and insoluble matters collecting in the bottoms of the bowls, as well as the mixture of solutions and suspended matters above the insoluble matters, are removed as desired, either continuously or intermittently.

and separated by a centrifugal into the three portions mentioned above and employed as therein described.

During the process, fresh water and scouring solutions are introduced into one of the latter bowls of the series, and hence, passes forwardly through the series in a reverse direction to the movement of the wool.

Further details of my process and device 10 will be evident upon a consideration of the following example of my invention.

In the accompanying drawings, which are graphic illustrations of one form of the device of my invention, similar parts are designated by similar numerals.

Figure 1 is a graphic side view of one form of my device.

Figure 2 is a top plan view of Figure 1.

In the accompanying drawings, my device 20 comprises a plurality of rectangular bowls 10, 11, 12, and 13 having their bottoms in the form of truncated pyramids.

Intermediate of the bowls 10—11, 11—12 and 12—13, are respectively a pair of 25 squeeze rollers 14, 14; 15, 15; 16, 16; a pair of guides 17, 17 being so situated with respect to the rollers as to act as a guide for wool passing from one bowl to the adjacent bowl through the intermediate squeeze rollers.

30 A downwardly extended pyramidal trough 18 is so situated as to catch the liquids from the squeeze rollers 14, 14, the lower end of the trough being connected to the centrifugal 19 by means of the pipe 20 having the valve 21.

The lower portion of the bowl 10 is connected to the pipe 20 by means of the pipe 22 having the valves 23 and 24.

The centrifugal 19 is connected to the 40 heater 25 by the grease discharge pipe 26 having the valve 27 and the heater 25 is connected to the centrifugal 28 by the pipe 29.

A pipe 30, feeding into the forward end of the bowl 10 is connected with the discharge 45 side of the centrifugal pump 31, the receiving side of which is connected to the centrifugal 28 by the pipe 32 having the valves 33 and 34.

The centrifugal 19 is connected to the pipe 50 32 between the valves 33 and 34 by the "cleaned liquor" pipe 35 having the valve 36.

A pipe 37, having the valve 38, connects the centrifugal 19 with a waste deposit, not 55 shown, and the centrifugal 28 has the exit pipe 39 having the valve 40.

Beneath the squeeze rollers 15, 15 is a trough 41, the lower portion of which is connected to the receiving side of the centrifugal pump 42 by the pipe 43 having the valve 44. The delivery side of the pump 42 is connected to the pipe 45 which delivers into the forward end of the bowl 11.

Beneath the squeeze rollers 16, 16 is a 60 trough 46, the lower portion of which is

connected to the receiving side of the centrifugal pump 47 by the pipe 48 having the valve 49. The delivery side of the pump 47 is connected to the pipe 50 which delivers into the forward end of the bowl 12.

70 A pipe 51 connects the liquids in the bowls 10 and 11, a pipe 52 connects the liquids in the bowls 11 and 12 and a pipe 53 connects the liquids in the bowls 12 and 13.

A pipe 54, having the valve 55, is connected to the pipe 20.

80 A pipe 56, having the valve 57, connects the bottom portion of the bowl 11 with the pipe 54 and a pipe 58, having the valve 59, connects the bottom portion of the bowl 12 with the pipe 54.

The operation of the device is as follows:—

The desired scouring, or washing, liquid is placed within the bowls 10, 11, 12 and 13 and the dirty, unwashed, wool is introduced into the bowl 10 and by means of rakes, is passed through the liquid in bowl 10 in the direction of the arrow A, the wool then passes through the squeeze rollers 14, 14 into the bowl 11, thence through the squeeze rollers 15, 15 into bowl 12, thence through the squeeze rollers 16, 16 into bowl 13 and thence outwardly in its cleaned condition.

85 The amount of water removed, associated with mud, is replaced by the addition of water to the bowl 13, as indicated by the arrow B, the same liquid level in all of the bowls being accomplished by means of the connecting pipes 51, 52 and 53. In this manner, the wool moves in the direction of the arrow A and the liquid in the reverse direction as indicated by the arrow B.

90 During this operation, the valves 23, 57 and 59 are closed, thus allowing an accumulation of the heavier dirt in the lower portion of the bowls.

95 The liquid from the squeeze rollers 16, 16 passes through the pipe 48, the pump 47 and the pipe 50 into the forward end of the bowl 12.

100 The liquid from the squeeze rollers 15, 15 passes through the pipe 43, the pump 42 and the pipe 45 into the forward end of the bowl 11.

105 The liquid from the squeeze rollers 14, 14 passes through the pipe 20 into the centrifugal 19. This centrifugal 19 is a "slow speed bulk" centrifugal, so constructed as to divide the liquid contents into three portions, due to their difference in specific gravity, viz mud, a grease mixture and a "cleaned liquid" containing the soluble salts and soaps, &c.

110 The mud passes outwardly through the pipe 37.

115 The "cleaned liquid" passes outwardly through the pipes 35 and 32, the pump 31 and the pipe 30 into the forward end of the bowl 10.

120 The grease mixture passes outwardly 130

through the pipe 26 and the heater 25 in which it is heated to about 180° F. to facilitate the separation of its component parts into the "high speed" centrifugal 28, in which it is separated into grease, passing outwardly through the pipe 39 and the "cleaned liquid" contents, passing outwardly through the pipe 32 to the forward end of the bowl 10.

When it is desired to remove the mud from the liquid contents of the bowl 10, the valves 23 and 24 of the pipe 22 are opened and the mud contents of the bowl 10 are thus introduced by gravity into the pipe 20 for treatment as above.

The removal and separation from the mud contents of the other bowls are simultaneously accomplished by opening the corresponding valves.

A consideration of the above shows that by the introduction of the proper amount of water and washing ingredients into the last, the purer liquid is automatically advanced against the movement of the wool, thus continually increasing the grease and cleansing ingredient content and dirt content of the first bowl and that the liquid in this first bowl is being continually automatically separated into its mud content which is eliminated, into grease which is eliminated and recovered and into the soluble salt and soap materials which are re-introduced into the forward end of the first bowl for the treatment of the newly introduced wool.

35 My process, therefore, avoids a concentration of grease emulsion in the first bowl to the extent of "striking back" upon the wool, and also avoids an accumulation of dirt in this bowl to the extent of retarding the 40 cleansing process.

In my device there is a constant movement of the soluble matters and emulsions toward the first bowl, thus leaving the scouring materials in the last bowls comparatively clean 45 and in such a condition as to allow of most effective final action upon the wool.

At the same time the accumulation of matters in the first bowl is being continuously removed and separated into their component 50 parts, thus allowing the liquor in the first bowl to be maintained at a uniform standard of composition, thus maintaining each of the remainder of the bowls at its particular standard.

65 The high concentration of the liquors of my process resulting from the treatment of wool, due to its steps of procedure, is a valuable feature in that it allows of more efficient and economical acid treatment of the liquors known in the industry as "cracking" and other desired treatments because of the smaller volume of liquor involved.

A consideration of the above description of my process and apparatus will disclose its novelty and many valuable features.

I do not limit myself to the particular size, shape, number or arrangement of parts, nor to the materials mentioned, nor to the exact sequence of steps described and shown above, as these are given simply by way of example, in order to clearly describe my invention.

What I claim is:—

1. In a continuous process for the recovery of wool grease from wool, the steps which comprise passing a scouring liquor through a series of receptacles, passing the uncleaned wool through the series of receptacles in reverse direction to the movement of the liquor, passing the wool between squeeze 75 rollers in its passage from one receptacle to the next receptacle, returning the squeezed liquid into the forward portion of the receptacle from which it was obtained, separating the liquor from the first squeeze rollers into mud, grease mixture and cleaned liquor 80 and returning the cleaned liquor to the wool treatment receptacle in which it has been taken up by the wool.

2. In a continuous process for the recovery 90 of wool grease from wool, the steps which comprise passing a scouring liquor through a series of receptacles, passing the uncleaned wool through the series of receptacles in reverse direction to the movement of the liquor, passing the wool between squeeze rollers in its passage from one receptacle to the next receptacle, separating the liquor from the first squeeze rollers into mud, grease mixture and cleaned liquor, returning the cleaned liquor to the receptacle from which it was removed and returning the liquor from each subsequent set of squeeze-rollers to the forward portion of the wool treatment receptacle in which it has been 100 taken up by the wool.

3. In a continuous process for the recovery 105 of wool grease from wool, the steps which comprise passing a scouring liquor through a series of receptacles, passing the uncleaned wool through the series of receptacles in reverse direction to the movement of the liquor, passing the wool between squeeze rollers in its passage from one receptacle to the next receptacle, returning the squeezed liquid into the forward portion of the receptacle from which it was obtained, separating the liquor from the first squeeze rollers into mud, grease mixture and cleaned liquor, returning the cleaned liquor 115 to the receptacle from which it was removed, separating the grease mixture into grease and cleaned liquor and returning the cleaned liquor thus obtained to the wool treatment receptacle in which it has been taken up by 120 the wool.

4. In a continuous process for the recovery 125 of wool grease from wool, the steps which comprise passing a scouring liquor through a series of receptacles, passing the uncleaned 130

wool through the series of receptacles in reverse direction to the movement of the liquor, passing the wool between squeeze rollers in its passage from one receptacle to the next receptacle, returning the squeezed liquid into the forward portion of the receptacle from which it was obtained, separating the liquid from the first squeeze rollers into mud, grease mixture and cleaned liquor, returning the cleaned liquor to the receptacle from which it was removed, re-

moving the mud contents from the bottom of the first receptacle, separating the cleaned liquor from the mud content and returning the cleaned liquor to the wool treatment receptacle in which it has been taken up by the wool. 15

Signed at New York city in the county of New York and State of New York this 13th day of November, 1922.

JOHN L. TUFTS.
